UNITED STATES PATENT OFFICE.

JOHN F. DAVEY, OF BEVERLY, MASSACHUSETTS, ASSIGNOR TO UNITED SHOE MANUFACTURING COMPANY, OF PATERSON, NEW JERSEY, A CORPORATION OF NEW JERSEY.

FASTENER-SETTING MACHINE.

1,244,430.

Specification of Letters Patent. Patented Oct. 23, 1917.

Application filed February 5, 1914. Serial No. 816,832.

To all whom it may concern:

Be it known that I, JOHN F. DAVEY, a citizen of the United States, residing at Beverly, in the county of Essex and State 5 of Massachusetts, have invented certain Improvements in Fastener-Setting Machines, of which the following description, in connection with the accompanying drawings, is a specification, like reference characters

10 on the drawings indicating like parts in the several figures.

This invention relates to machines for setting fasteners in sheet material and is herein disclosed as embodied in a machine intended 15 primarily for setting eyelets in gloves and the like, although many of its features may be employed with good advantage in machines for setting eyelets or other fasteners in parts of boots and shoes.

20 One object of the invention is to provide a machine of such construction that it may be operated either mechanically or by foot power without substantial change in general organization. Such a machine is advan- 25 tageous because it can be used in a larger field than a machine which is adapted to be operated only mechanically or only by foot power.

In this connection an important feature 30 of the invention consists in the provision of toggle mechanism for operating the movable setting die so disposed that a treadle rod may be connected adjacent to its knuckle joint when it is desired to operate the 35 machine by foot power, said mechanism being at the same time adapted to be connected to power actuating means when it is desired to operate the machine by power.

Another feature of the invention relates 40 to the provision of a novel form of punching mechanism whereby the work may be perforated preliminarily to the insertion and clenching of an eyelet. As herein shown the punching mechanism is arranged to be 45 operated by foot power from a treadle and suitable connections are provided whereby the initial movement of the treadle is effective for actuating the punching device while its further movement is effective for 50 throwing the clutch into engagement and so setting the machine in operation. Another feature of the invention relates more broadly to the organization of the punching and setting mechanism of a fastener setting ma-

chine, and consists in providing a pair of 55 setting devices and a pair of punching devices, together with power operated mechanism for effecting the action of one of said pairs and manually operated mechanism for effecting the action of the other of said pairs. 60 It is believed that this combination has never before been employed in a fastener setting machine.

Still another feature of the invention relates to the mechanism for moving the raceway to and from its delivering position. It is desirable that the machine should come to rest with its raceway in its delivering position and that the raceway should be moved out of range of the setting die as 70 soon as the machine is set in operation and maintained in an inoperative position until after the setting operation so that there will be no danger of striking the setting die. This is effected, as herein shown, by providing a 75 sliding cam bar movable to displace and hold the raceway and adapted to be actuated either from the main shaft, when the machine is operated mechanically, or from some point in the mechanism for actuating the 80 setting device when the machine is to be operated by foot power.

Other features of the invention consist in an improved general organization whereby the machines may be adapted for various 85 different classes of work and whereby an improved mechanical arrangement of the moving parts is secured. As herein shown the machine frame is provided with a detachable jaw for holding one of the setting 90 devices, the arrangement being such that other jaws of different shapes may be substituted as occasion may require. Parts of the raceway actuating mechanism are so associated with parts of the starting and stopping mechanism that a common mounting 95 may be utilized and the machine thus simplified in this respect.

These and other features of the invention will be best understood and appreciated 100 from the following description of a preferred embodiment thereof selected for purposes of illustration and shown in the accompanying drawings, in which,—

Figure 1 is a view of the machine in side 105 elevation;

Fig. 2 is a view in elevation, partly in section, of the other side of the machine;

Fig. 3 is a fragmentary view of the raceway and connections;

Fig. 4 is a view in side elevation of portions of the starting and stopping mechanism;

Fig. 5 is a view in perspective of these and other portions of the starting and stopping mechanism;

Fig. 6 is a fragmentary view showing the 10 punching die and lower setting device in initial position;

Figs. 7, 8 and 9 are views in perspective showing the operating parts of the machine in different positions, and

15 Fig. 10 is a view in section showing the setting devices in clenching position.

The machine frame 2 has bolted to it a detachable lower jaw 4 having at its outer end a split socket for the lower setting device 6 which is adjustably maintained in position by a clamping bolt 8. The jaw 4 is made detachable so that it may be replaced by other jaws of different shapes in case it is desired to adapt the machine for any 25 particular class of work. To insure properly locating the jaw the frame is provided with a shouldered surface and the base of the jaw is shaped to fit the surface of the frame.

30 The upper portion of the frame is provided with vertical bearings for the reciprocating plunger 10 which carries at its lower end the upper setting die 12. The die 12 is shaped at its end to fit the flange of the eyelets to be set and is provided with a yielding center spindle 14. The plunger 10 is reciprocated by connections with toggle links 20 and 22, the toggle links being so disposed as to occupy a substantially horizontal position as the upper setting die 12 approaches its clenching position. The plunger 10 is connected at its upper end to a short link 18 which in turn is connected to the forward end of a bell crank lever 16 45 pivotally mounted on the shaft 17. The lower end of the bell crank lever 16 is connected to the toggle link 20 which is U-shaped and has one branch extending on each side of the lever 16 and of the other toggle link 22. The toggle links and the lever 16 are disposed within the machine frame and the link 22 has a projection perforated at 23 for connection with a treadle rod in case the machine is to be operated by 50 foot power. The machine is herein shown as adapted to be operated from the power driven shaft 30 and consequently the treadle rod by which the toggle might be straightened is omitted from the drawings.

55 The toggle link 22 is secured to a rock shaft 24 which extends through the sides of the machine frame and is provided on one end with a crank arm 25 as shown in Fig. 2. The arm 25 is connected through an oscillatory link 26 to a crank pin 28 which pro-

jects from a disk fast on the driving shaft 30. When the shaft 30 is turned from the position shown in Fig. 2 the link 26 is moved forwardly, the toggle straightened and the forward end of the lever 16 depressed, thus 70 lowering the setting die into clenching position.

Eyelets are supplied to the setting die 12 by a raceway 68 mounted upon a journal pin 70 extending between upstanding ears 75 on the machine frame. The raceway carries a hopper 66 of the usual construction. The latter contains an agitator arranged to be actuated by a crank arm 64 through connections with the bell crank lever 16. For this purpose a stud 62 is provided on one side of the lever 16 and is arranged to oscillate an interposed bell crank lever 60 which is connected through a universal joint to the crank arm 64.

80 The raceway 68 is yieldingly maintained in its delivering position by a spring actuated rod 69 pivotally connected at one end to a stud 67 on the raceway and extending through the machine frame to the opposite 90 side where it is provided with a retaining nut. The raceway, after delivering an eyelet, is swung outwardly against the compression of a spring which encircles the rod 95 69 and the latter, when permitted, swings the raceway inwardly to a delivering position determined by an adjustable stop set in the machine frame as shown in Fig. 7.

For the purpose of moving the raceway 100 out of its delivering position there is provided, between the raceway and the machine frame, a cam bar 74 having a tapering end arranged to engage a roller 72 on the raceway. The cam bar is slotted at its lower end and guided in its reciprocatory movement by a stud 63 set in a boss on the machine frame as shown in Fig. 7. The cam bar 74 is reciprocated in a path parallel to the length of the raceway by a cam lever 76 105 pivotally mounted on the transverse shaft 110. 36 and carrying at its rear end a cam roller which runs upon a cam 78 on the driving shaft 30. The shape of the cam 78 is shown in dotted lines in Fig. 4 from which it will be seen that the lever 76 is oscillated to move 115 the raceway outwardly early in the cycle of the machine and held outwardly until just before the machine is brought to rest.

In order to perforate the work preliminarily to inserting an eyelet there is provided a sectional punching die plate comprising the two sections 82. These are arranged to force the work upon the sharpened spindle of the lower setting die 6 to 120 perforate the work and are then separated to 125 permit the passage of an eyelet. The punching die sections 82 are pivotally mounted upon the carrying bar 80 which in turn is mounted to swing vertically about a horizontal shaft 81 as an axis. The punching 130

die is depressed through the treadle rod 85 connected to the treadle 86 and is returned to its initial position by a compression spring which encircles the upper end of the 5 treadle rod and rests on the base of the frame as shown in Fig. 1. The upper or initial position of the bar 80 is determined by an adjustable stop 83 and its lower position is limited by an adjustable stop 81 in the jaw 10 4. Secured to the lower face of the bar 80 is a thin plate 84 perforated to fit over the lower setting die 6 and arranged to act as a stripper for removing the work with a clenched eyelet from the spindle of the lower 15 setting die 6 after the setting operation.

The driving shaft 30 has secured thereon a hand wheel 32 and a pulley 34 by which the machine may be driven from any suitable source of power. The pulley 34 normally runs loosely upon the shaft but is 20 adapted to be clutched thereto whenever the clutch ring 38 shown in Fig. 5 is released. This ring comprises part of the well known Horton clutch. The clutch ring 38 is held 25 in position for causing the clutch to remain disengaged by a stop arm 40 secured to the rock shaft 36. When it is desired to start the machine the arm 40 is lowered out of the path of the projection on the clutch ring 38. 30 It is desirable to prevent non-repeating action of the clutch and to this end mechanism is provided for returning the arm 40 to stopping position after it has once been depressed far enough to permit the machine to 35 start. Loosely mounted on the rock shaft 36 is a tripping arm 44 carrying a dog 46. The dog 46 is arranged to hook over a projection 50 on an arm 52 which is fast to the rock shaft 36. A cam 47 on the driving 40 shaft 30 is arranged to swing the dog 46 out of engagement with the projection 50 as soon as the machine has been started and hold it in a disengaged position until one cycle of the machine has been completed. 45 When the dog 46 has been disengaged from the projection 50 on the lever 52 the latter is immediately moved upwardly by a compression spring which bears on its rear end and the rock shaft 36 rotated to bring the 50 stop arm 40 into the position shown in Fig. 5.

In order to insure a prompt stopping of the machine an eccentric disk 56 is mounted upon the driving shaft 30 and a brake shoe 55 54 is connected by a link 60 to a short arm on the rock shaft 36 so that the brake will be withdrawn or applied simultaneously with disengaging or engaging the clutch. A handle 58 is operatively connected with 60 the brake shoe 54 so that the latter may be loosened in case it is desired to turn the driving shaft by hand. A spring presser pin 62 tends normally to move the clutch shoe into operative position.

65 When the machine is operated by power

the treadle rod 42 by which the clutch is controlled has a lost motion connection with the treadle 86, the arrangement being such that the initial depression of the treadle 86 will swing the punching die for perforating 70 the work and its further movement will depress the clutch rod 42 and permit the clutch to become engaged.

When the machine is operated under power the raceway is moved by the mechanism above described but when the machine is operated by foot power the cam lever 76 is replaced by an arm 100 which may be secured to the outer end of the rock shaft 24 and provided with a boss to make connection with the cam bar 74 similar to that made by the cam lever 76. The arm 100 is indicated in dotted lines in Fig. 1.

In operating the machine the material in which the eyelet is to be set is introduced 85 between the stripper 84 and the punching die 82. The treadle is then depressed and the work forced downwardly upon the perforating spindle of the lower setting die. As the point of the spindle passes through the 90 work it enters between the sections of the punch die 82 and slightly separates them as indicated in Fig. 7. Meanwhile the lost motion between the treadle and the clutch rod 42 has been taken up so that further depression of the treadle swings downwardly the tripping arm 44 and, through the mechanism above explained, causes the clutch to become engaged and the machine started. Thereupon the upper setting die is lowered 100 first to engage with its spindle the endmost eyelet in the raceway and then, as the raceway is withdrawn, to separate the punching die sections, insert the eyelet and finally 105 clench it against the lower setting die. The power actuated parts are subsequently returned to their initial position and the machine stopped. Then, when the treadle is 110 released, the punching die plate and stripper 115 84 are raised and the latter removes the work and the clenched eyelet from the lower setting die, thus leaving the machine in condition for setting a new eyelet.

Having thus described my invention, what I claim as new and desire to secure by Letters Patent of the United States is:

1. A fastener setting machine, having in combination, setting devices, power operated actuating mechanism therefor, a punching device, and a treadle for actuating the 120 punching device in its initial movement and throwing into operation the power operated actuating mechanism by its further movement.

2. A fastener setting machine, having in combination, setting devices, power operated actuating mechanism therefor, relatively 125 movable punching devices, and means arranged to be moved manually to effect the punching operation in its initial movement 130

- and to throw the power operated actuating mechanism into operation by its further movement.
3. A fastener setting machine, having in combination, a power driven shaft, a clutch thereon, a setting device arranged to be actuated by the shaft, a movable punching device, and a treadle so connected to the clutch and punching device as to cause the punching device to be operated prior to throwing in the clutch.
4. A fastener setting machine, having in combination, setting devices, a punching die maintained at all times in co-axial relation with the setting devices and pivotally mounted for movement about an axis at one side of the setting devices, manually operated means for swinging the die to perforate the work, a stripper mounted on the die, and means for returning the die and stripper to their initial positions.
5. A fastener setting machine, having in combination, a power driven shaft having a crank, an oscillating connecting rod actuated thereby, a rock shaft connected to the rod and oscillated thereby, a reciprocatory setting device mounted for movement in a path adjacent to the rock shaft, and a connecting lever mounted for oscillation about an axis located on the side of the rock shaft remote from the path of the setting device and operated from the rock shaft.
6. A fastener setting machine having, in combination, setting dies arranged for relative vertical movement to effect the setting operation, and actuating mechanism including a pair of toggle links arranged to occupy a substantially horizontal position when straightened to force the setting dies together.
7. A fastener setting machine having, in combination, a normally stationary setting die, a co-operating setting die movable toward and from the latter, and toggle links for actuating the movable die arranged to extend substantially at right angles to the path of the movable setting die when straightened.
8. A fastener setting machine, having in combination, setting dies arranged for relative vertical movement, power actuating means, and toggle links interposed between one of said dies and said actuating means and being arranged to occupy a substantially horizontal position when straightened, the link located farthest from the movable die being connected to said die.
9. A fastener setting machine, having, in combination, a frame carrying a pivotally mounted raceway and a reciprocatory set-

ting die, a cam bar arranged to slide in a path substantially parallel to the raceway, means for yieldingly holding the raceway toward the setting die, and independent trains of mechanism for operating the setting die and the cam bar.

10. A fastener setting machine, having, in combination, a reciprocatory setting die, a movable raceway associated therewith, a cam bar arranged for movement in a path parallel to that of the setting die, and independent trains of mechanism for so moving the cam bar and setting die respectively, as to hold the raceway away from the setting die while the die is between two predetermined points in its path.

11. A fastener setting machine, having in combination, a stationary member having a setting portion and a punching portion, a manually operated punching member movable to effect the punching operation, and a power operated setting member movable to effect the setting operation.

12. A fastener setting machine having, in combination, co-operating setting dies, a power shaft arranged to actuate one of said dies, a movable raceway, a clutch and cam carried by the power shaft, a rock shaft disposed in parallel relation to the power shaft, a clutch tripping lever carried by said rock shaft, and a raceway actuating lever journaled on said rock shaft and arranged to be actuated by the cam on the power shaft.

13. A fastener setting machine, having in combination, a pair of punching members and a pair of setting members maintained at all times in substantially co-axial relation, power operated actuating mechanism for effecting the operation of one pair, and manually operated actuating mechanism for effecting the operation of the other pair.

14. A fastener setting machine, having, in combination, a frame, a reciprocatory setting die mounted therein, a pivotally mounted raceway movable toward and from the die, a rod connected to the raceway beneath its axis and extending transversely through the machine frame, said rod serving to hold the delivery end of the raceway beneath the die, and independent trains of mechanism for moving the die downwardly and the raceway outwardly in timed relation.

In testimony whereof I have signed my name to this specification in the presence of two subscribing witnesses.
